DESIGN FOR A FOLDING SEAT

Lucien G. Brouillard, Minneapolis, Minn.

Application January 12, 1940, Serial No. 89,434

Term of patent 7 years

To all whom it may concern:

Be it known that I, Lucien G. Brouillard, a citizen of the United States and residing in the city of Minneapolis, Hennepin County, State of Minnesota, have invented a new, original, and ornamental Design for a Folding Seat, of which the following is a specification, reference being had to the accompanying drawing, forming a part thereof, wherein,

Fig. 1 is a perspective view illustrating a folding seat in extended position showing my new design; Fig. 2 is a view in front elevation of the same in folded condition;

Fig. 3 is a view in front elevation of the lower part of the seat when in extended position as shown in Fig. 1.

I claim:

The ornamental design for a folding seat, substantially as shown.

LUCIEN G. BROUILLARD.
